Atty's

UNITED STATES PATENT OFFICE.

JOHN MACGREGOR, OF CHICAGO, ILLINOIS, ASSIGNOR TO COOK LABORATORIES, INC., OF CHICAGO, ILLINOIS, A CORPORATION OF DELAWARE.

HYPODERMIC SYRINGE.

Application filed September 15, 1924. Serial No. 737,636.

This invention relates to hypodermic syringes of the type employing a medicament-dispensing cartridge as the medicament container, and among other objects aims to 5 provide a syringe exceptionally easy to fill with such a cartridge.

The invention may be understood by reference to one illustrative embodiment shown in the accompanying drawings, in 10 which:

Fig. 1 is an elevation of the syringe;

Fig. 2 is an enlarged longitudinal cross-section thereof; and

Fig. 3 is an elevation of the principal 15 parts of the syringe shown open for filling.

It is to be understood that the illustrative form shown in the drawings is simply a preferred embodiment of the invention; and that in the following explanation of that 20 specific form, the described details of structure and organization are merely exemplary.

The syringe shown comprises a skeleton barrel or body 5 to which a tubular cartridge carrier member 6 is swingably connected intermediate 25 its length by rivets 7. When the barrel is closed, as shown in Fig. 1, the carrier member is axially aligned with the barrel, and its ends lie adjacent the barrel heads 8 and 9. The barrel head 8 supports the hypodermic needle 10, while the barrel head 9 slidably receives the syringe plunger rod 11 which contracts the interior volume of the cartridge 12 to dispense its contents through the needle. To fill the syringe, the 30 carrier 6 is swung on its pivots, as shown in Fig. 3, thus presenting either of its ends in convenient position for insertion of a fresh cartridge.

To hold the barrel closed, the barrel head 40 9 carries a lock 13 in the form of a slidable, hollow sleeve, normally projected outwardly from the barrel head by a spring 14. The lock is designed to fit in one end of the pivoted cartridge carrier to keep it aligned 45 with the plunger, so that the inner enlarged end 15 of the plunger rod may push the slidable plug 16 of the cartridge to inject the medicament. As shown, the plunger end 15 engages with a recess 17 in the sleeve lock, permitting disengagement of the lock by an outward pull on the plunger rod. When the cartridge is within the locked

carrier, the outer edge of the sleeve lock presses the cartridge resiliently toward the needle (Fig. 2), thus preventing an objectionable looseness of assembled parts, as 55 will be explained below.

In the construction shown, the carrier is pivoted midway its ends and midway the barrel heads 8, 9 so that the carrier may be 60 swung in either direction in opening or closing the syringe. As best shown in Fig. 3, the end edges of the tube which forms the carrier may be cut away on opposite sides as at 18, so that when the carrier is moved 65 toward closed position, its cut-away edge cams the sleeve lock, which yields to the carrier. Such a construction permits the 70 syringe to be snapped shut without manipulating the lock.

Before using the syringe, the carrier 6 is unlocked and swung outwardly, as shown in Fig. 3, and the cartridge is inserted in either end. Then the carrier is moved into longitudinal alignment with the barrel, 75 whereupon the lock automatically snaps shut, as described. Lastly, the cartridge plug 19 is pierced by a longitudinal thrust of the needle, which then provides a medicament conduit leading from the interior of the 80 cartridge to the point of injection. The 75 syringe is now ready for service.

When the syringe is used, the plunger 11 pushes the slidable plug 16 through the cartridge, ejecting the medicament through 85 the fine bore of needle 10. Due to the large ratio of the diameter of the slidable plug to the bore of the needle, a small movement of the former causes a rapid flow through the latter, whose flow capacity is very limited; and the resultant fluid pressure within the cartridge is sufficient to tend to eject plug 19, which would cause loss of the medicament and fouling of the syringe. In the arrangement shown, the spring-pressed 90 latch 13 presses the cartridge firmly against the syringe head 8, thus adding the resistance of the spring 14 to the frictional grip of plug 19 within its tube; and these 95 two resistances are usually sufficient to prevent positively any outward movement of plug 19.

Obviously the present invention is not restricted to the particular embodiment there-

of herein shown and described. Neither is it indispensable that all the features of the invention be used conjointly; they may be employed advantageously in various combinations and sub-combinations as defined in the claims.

What I claim is:

1. A hypodermic syringe comprising, in combination, a skeleton barrel; a cartridge holder pivoted intermediate its ends to an intermediate point of said barrel and open at one end for insertion of the cartridge; and means for locking the cartridge holder to the barrel when coaxial therewith.
2. A hypodermic syringe comprising, in combination, a supporting body; a cartridge-enclosing member pivoted to the body to swing about a transverse axis between its ends, both of which are open for insertion of the cartridge, and a latch serving to lock the cartridge-enclosing member in axial alignment with the body.
3. A hypodermic syringe comprising, in combination, a body; and a cartridge carrying member pivoted to the body and open at one end for ready insertion or removal of the cartridge; the parts being so constructed and arranged that the carrying member may be swung or rotated on its pivots but is otherwise immovable relative to the body.
4. A hypodermic syringe comprising, in combination, a body; and a cartridge carrying member pivoted to the body and open at one end for ready insertion or removal of the cartridge; and a spring latch carried by the body for locking the cartridge-enclosing member in a position permitting dispensing of the medicament therefrom.
5. A hypodermic syringe comprising, in combination, a skeleton barrel; a cartridge holder pivoted intermediate its ends to said barrel and constructed and arranged to enclose a cartridge placed therein; a plunger slidable through one end of the barrel to dispense medicament from the cartridge; and a latch for holding together the barrel and cartridge holder, said latch being released by pulling on the plunger.
6. A hypodermic syringe comprising, in combination, a skeleton barrel; a cartridge holder carried by the barrel and constructed and arranged to permit insertion of a cartridge therein from one end; and a spring latch carried by the barrel and fitting into one end of the cartridge holder; the parts being so constructed and arranged that when the cartridge is in the holder and the latch is engaged, the cartridge is pressed against the other end of the barrel by the spring latch.
7. A hypodermic syringe comprising, in combination, a barrel; a cartridge holder carried by the barrel; the barrel and cartridge holder being relatively movable to permit insertion of a cartridge from either

end of the holder; and a plunger carried by the barrel for dispensing medicament from the cartridge.

8. A hypodermic syringe comprising, in combination, a rigid, skeleton barrel having heads at opposite ends; a cartridge holder, tubular in form, pivoted at an intermediate point to the barrel and swingable outwardly therefrom for insertion of a cartridge; a hypodermic needle; means securing said needle to one of the barrel heads to extend therethrough in position to pierce one end of the cartridge; a latch carried by the opposite barrel head and constructed and arranged to engage the cartridge holder to retain it coaxial with the barrel; and a medicament-dispensing plunger slidable through said opposite head.

9. A hypodermic syringe comprising, in combination, a rigid skeleton barrel having heads at opposite ends; and a tubular, open-ended cartridge holder pivoted intermediate its ends to the skeleton barrel and fitting within the barrel when swung into axial alignment and presenting either end for filling with a cartridge when swung out of alignment with the barrel.

10. A hypodermic syringe comprising, in combination, a skeleton barrel; a tubular cartridge holder pivoted midway its ends to said barrel; a spring lock carried by the barrel and constructed and arranged to engage with either end of the cartridge holder when co-axial with the barrel; the end edges of said cartridge holder being cut away so that when either end is swung toward the lock from either direction, the edge of the holder cams the lock which snaps shut automatically.

11. A hypodermic syringe comprising, in combination, a rigid skeleton barrel including heads at opposite ends and tie members connecting the heads; a tubular cartridge-enclosing member pivoted between the tie members at a point midway between the ends thereof and of the tie members, and freely swingable but otherwise immovable relative to the barrel; a manually operable latch carried by one of the syringe heads and projectable across the joint between said head and an end of the cartridge-enclosing member so as to extend a short distance within said member; a medicament dispensing cartridge held in place by said latch; and means on the other syringe head for supporting a needle in cartridge-piercing position.

12. A hypodermic syringe comprising, in combination, a rigid skeleton barrel including heads at opposite ends and tie members connecting the heads; a tubular cartridge-enclosing member pivoted between the tie members at a point midway between the ends thereof and of the tie members, and freely swingable but otherwise immovable relative to the barrel; a spring pressed

sleeve lock carried by one of the syringe heads and projected by the spring across the joint between said head and an end of the cartridge-enclosing member so as to extend a short distance within the member; a medicament dispensing plunger reciprocable through said head and engaging the sleeve lock so as to withdraw the lock from the cartridge-enclosing member when pulled outwardly. ¹⁰

In testimony whereof, I have signed my name to this specification.

JOHN MacGREGOR.
